Primary Examiner—Cynthia M Chin*(74) Attorney, Agent, or Firm*—Wenderoth, Lind & Ponack, LLP.(57) **CLAIM**

The ornamental design for a toy block, as shown and described.

DESCRIPTION

FIG. 1 is a perspective view of a toy block showing our new design;

FIG. 2 is a front view thereof, the rear view being a mirror image thereof;

FIG. 3 is a top plan view thereof;

FIG. 4 is a right side elevation view thereof, the left side elevation view being a mirror image thereof;

FIG. 5 is a bottom view thereof;

FIG. 6 is a sectional view thereof taken along line 6—6 of FIG. 2;

FIG. 7 is a sectional view thereof taken along line 7—7 of FIG. 3;

FIG. 8 is a perspective view showing how the toy block is used; and,

FIG. 9 is another perspective view showing how the toy block is used.

The broken lines in FIGS. 8 & 9 show the design in use and form no part of the claim.
